(57) **CLAIM**

The ornamental design for a portable heater and air purifying unit, as shown and described.

DESCRIPTION

(21) Appl. No.: **29/433,892**

FIG. 1 is a front top perspective view of a portable heater and air purifying unit showing my new design.

(22) Filed: **Oct. 5, 2012**

FIG. 2 is a front view of the face of the portable heater and air purifying unit of FIG. 1.

(51) **LOC (10) Cl. 23-03**

FIG. 3 is a right side view of the front face of the portable heater and air purifying unit of FIG. 1.

(52) **U.S. Cl.**

FIG. 4 is a top view of the front face of the portable heater and air purifying unit of FIG. 1.

(58) **Field of Classification Search**

FIG. 5 is a bottom view of the front face of the portable heater and air purifying unit of FIG. 1.

USPC D23/314, 332, 335-350, 378, 370, 381,

FIG. 6 is another front top perspective view of front face of a portable heater and air purifying unit of FIG. 1, but showing its adjustable air flow grill in a tilted up direction; and,

D23/354, 351, 386, 333, 328, 353, 361, 385, D23/417, 357, 364; 126/183, 110 B, 91 A, 126/92 A, 500, 544, 547; D13/184; 96/58, 96/63, 75, 80, 97; 361/235; 363/142

FIG. 7 is another front top perspective view of front face of a portable heater and air purifying unit of FIG. 1, but showing its adjustable air flow grill in a tilted down direction.

See application file for complete search history.

Features shown in dashed lines do not form part of the design.
